UNITED STATES PATENT OFFICE

WALTER SCHULZ AND HELLMUT HOFFMANN, OF SYDOWSAUE, NEAR STETTIN, GERMANY, ASSIGNORS, BY MESNE ASSIGNMENTS, TO AMERICAN GLANZSTOFF CORPORATION, OF NEW YORK, N. Y., A CORPORATION OF DELAWARE

PROCESS FOR THE WORKING UP OF CENTRIFUGE SILK

No Drawing. Application filed August 30, 1929, Serial No. 389,604, and in Germany April 10, 1929.

This invention has for its object to simplify the after treatment of centrifugally spun artificial silk particularly in respect of the steps leading up to the use of such silk on textile machines. A further object is to provide a simple method of treating spun cakes of artificial silk so that they can be used directly on textile machines without preparatory re-winding.

10 In the working up of centrifuge silk the spun cakes, either moist—in unwashed or in washed condition—or washed and already dried, have hitherto been brought into hank form. The cleaned and dried hank silk was then, for the purpose of further treatment, either in the artificial silk works or after reaching the consumer, rewound, or re-reeled on auxiliary spools (so called cross wound bobbins, cops, taper bobbins, or pirns) which 15 auxiliary spools were then in the known way, set up on the textile working up machines for the production of textile goods.

The present invention relates to the further working up of any kind of artificial silk 20 spun by the centrifugal method, whether it be viscose silk, ammonical copper oxide silk, nitro silk or acetate silk, and in particular to the further working up of the spun cakes obtained by this method, cleaned or freed from deleterious chemicals and dried. In contradistinction to the mode of procedure hitherto employed, however, the spun cake, is not only no longer re-reeled into the hank form, but the intermediate production of auxiliary 25 spools such as cross wound bobbins, cops, taper bobbins, or pirns is rendered superfluous for many purposes in the working up of artificial silk.

According to the present invention it has 30 been found that the cleaned and well dried spun cakes, when they are carefully handled and their layers of thread are not tangled when washing, drying and so forth, are predominantly suitable for being presented directly to the actual textile working machines, i. e. the machines for the production of textile goods, such as knitting machines, circular looms, stocking machines, warping machines, doubling machines and the like. All 35 cases are included here wherein the auxiliary

spools hitherto employed from which the artificial silk filament is drawn into the machine in which it is treated being fixedly located.

For the purpose of the present abbreviated 35 textile treatment process it has as already mentioned been found indispensable that the washed and dried spun cakes be presented in an untangled state for further treatment. In order to obtain the spun cakes in this state 40 it is advisable to carry out the washing and subsequent treatment of the spun cakes by carefully wrapping each cake in a flat compressed state in protecting, easily permeable wrappings, e. g. consisting of artificial silk or cotton yarn, and putting a greater number of the so treated cakes in layers into washing centrifuges which are sufficiently unattackable by the liquids employed for treatment, washing and subsequently treating 45 them. Similar good results were obtained by hanging the spun cakes compressed into flat hanks and wrapped in protecting, easily permeable textile or net-like wrappings on horizontal bars and subjecting them in 50 the trickling process to the well known washing out and other subsequent treatment processes.

Finally the spun cakes may also be carefully cleaned for the purposes of this process 55 by subjecting them, still in the spinning centrifuge or in corresponding rotating vessels to a spray treatment with appropriate cleansing baths. The procedure may also be such that the spun cakes are laid together 60 into a flat hank and, before or after being so laid together, are wrapped in an easily permeable, net-like or other textile material, e. g. of artificial silk, or bound round with a system of lacing threads in order to secure 65 the mutual position of the threads therein, and then treated by spraying or immersion with the necessary cleaning and treating baths.

The spun cakes washed or cleaned in one way or another and desulphurized if necessary or even undesulphurized, bleached or otherwise subsequently treated, and in all cases free from injurious chemicals may then

be used at once in a well dried condition according to the new process.

The cakes thus cleaned and dried may also be adapted for transport over long distances, for instance, in a flattened compressed condition and packing them appropriately. After being unpacked and opened at the place of destination into their original annular form they may be worked up directly according to the new process. The packing, for instance, may be effected in such a manner that the cakes are formed into flat hanks and wrapped into a protective net-like cover, which hanks are piled into strong cardboard boxes employing intermediate layers between the superposed hanks, so that the cakes will not be able to shift in the said boxes.

In the working up of the aforesaid spun cakes premature collapse when drawing off the thread endwise is avoided by inserting in the interior of the cake a loosely fitting conveniently elastic stiffening ring of rubber, celluloid, sheet metal or the like, as is usually practised and well known when reeling off the spun cakes into hank form. Stationary devices may also be applied to the textile machines themselves which act in a similar manner to the stiffening rings and these devices may take the form of a cone, an elastic ring etc. In certain cases it has been found useful to place the spun cakes when working the silk off on the textile machines on easily rotatable supports. In such case the movable support may take the form of a disc, on which the cake is put down or it may take the form of a reel, the axis of which is mounted horizontally or the like.

For the successful direct working up of spun cake on textile machines it has been found to be of considerable importance that the artificial silk thread shall possess sufficient suppleness and ability to slide when run on to the textile-machine. According to the invention this is ensured by previously treating the thread with the well known textile oils, textile fats and the like. For example, the thread may be passed on its way to the machine through a well known apparatus such as an oiler, wherein it is brought into contact with agents which make it supple and capable of sliding.

According to the particular nature of the textile machine of which the artificial silk is to be worked up, the thread running in must sometimes possess a greater or smaller tension. However, the thread on the spun cakes to be directly worked up rests, in this case, quite loosely on the cakes so that when unwound from the cake the automatic tension produced is not sufficient for many purposes of the working up process. Consequently it is necessary in these cases to arrange after the cake a well known auxiliary member in the form of a so-called thread tensioner, thread brake or the like.

We claim:

1. In the production of textile goods from centrifugally spun artificial silk the method in which the spun cake produced in the centrifuge after being freed from injurious chemicals and dried, is set up directly on the textile machine and used thereon. 70
2. In the production of textile goods from centrifugally spun viscose silk the method wherein, washed and dried cake from the centrifuge is worked up directly on textile machinery. 75
3. In the production of textile goods from centrifugally spun artificial silk, the method in which a spun cake is wrapped in a permeable wrapping, pressed flat, cleansed while in this condition, dried and used directly on a textile machine. 80
4. In the production of textile goods from centrifugally spun artificial silk, the method in which a spun cake is pressed flat, wrapped in a permeable wrapping cleansed in a centrifugal device while in this condition and subsequently unpacked dried and used directly on a textile machine. 85
5. In the production of textile goods from centrifugally spun artificial silk, the method in which a spun cake is pressed flat, wrapped in a permeable wrapping suspended on bars and cleansed while in this condition and subsequently unpacked dried and used directly on a textile machine. 90
6. In the production of textile goods from centrifugally spun artificial silk, the method wherein spun cakes from the centrifuge are formed, after cleaning and drying, into a flat hank, compressed, transported in this flat compressed condition, opened out into their original annular form and then used directly on the textile machines. 100
7. In the production of textile goods from centrifugally spun artificial silk the method wherein the spun cakes after being washed and dried are mounted directly on stiffening supports on the textile machines. 105
8. In the production of textile goods from centrifugally spun artificial silk the method wherein the threads of the cleaned and dried spun cakes are oiled and used directly on the textile machines. 110
9. In the production of textile goods from centrifugally spun artificial silk, the method in which a spun cake is laced round with threads, cleansed while in this condition, dried and used directly on a textile machine. 115
10. In the further working up of artificial silk spun by the centrifugal method, the process comprising freeing the spun cake from deleterious chemicals, drying it and working it up directly on a textile machine. 120
11. In the further working up of artificial silk spun by the centrifugal method, the process comprising subjecting the cake still in the spinning centrifuge to a spray treatment with appropriate cleansing baths, dry- 125

ing it and working it up directly on a textile machine.

12. In the manufacture of artificial filaments by the centrifugal method, the step of treating the cake and then using it directly on a textile machine.

In witness whereof we have hereunto signed our names.

WALTER SCHULZ.
HELLMUT HOFFMANN.
